UNITED STATES PATENT OFFICE

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE

BUTTONHOLE SEWING MACHINE

Application filed April 14, 1928. Serial No. 269,985.

This invention relates to buttonhole sewing machines and particularly to means for trimming the thread and cutting the buttonhole slit at the end of the sewing operation.

The invention is herein shown as applied to a two-thread buttonhole sewing machine and it comprises means for cutting both the upper thread and the under thread (and stay cord also, if one is used).

According to one feature of the invention the means for cutting one of the threads is carried and operated by the buttonhole cutting mechanism so that at the end of the buttonhole the operation of cutting the buttonhole also results in cutting one of the threads.

The buttonhole sewing machine herein shown is of that type adapted to sew a buttonhole with an eye and in which the stitch-forming mechanism is mounted to rotate at each end of the buttonhole.

According to another feature of the invention the means for cutting the other thread is arranged to be actuated by the devices for rotating the stitch-forming mechanism so that as the stitch-forming mechanism is turned at the end of the buttonhole the thread will at the same time be severed.

Another feature of the invention relates to novel means for holding the under thread after it is cut and until the first stitches have been made on the next succeeding buttonhole thereby ensuring the proper formation of the first stitches.

Other features of the invention relate to various improvements in buttonhole sewing machines all as will be more fully herein-after set forth.

In order to give an understanding of the invention I have illustrated in the drawings a selected embodiment thereof which will now be described after which the novel features will be pointed out in the appended claims.

Fig. 1 is a side view of a sewing machine embodying my invention;

Fig. 2 is a plan view of the work-supporting portion of the bed with the clamp plates removed to show the turret, part of the buttonhole cutting mechanism and the cutter for the upper thread;

Fig. 3 is a section on the line 3—3 of Fig. 2;

Fig. 4 is an under side view of the bed showing the means for actuating the under thread cutter;

Fig. 5 is a front elevation of the head showing the pull-off for the upper thread;

Fig. 6 is a fragmentary view illustrating the cutter for the under thread and stay cord;

Figs. 7 and 8 are views of two opposite sides of the turret and under thread mechanism;

Figs. 9 and 10 are views of the under thread mechanism illustrating the tension release for the under thread and the under thread gripping device;

Fig. 11 is a fragmentary plan view of the turret illustrating the means for actuating the under thread gripping device;

Fig. 12 is a section on the line 12—12, Fig. 9;

Fig. 13 is a fragmentary view showing the buttonhole cutters in operative position;

Fig. 14 is a plan view similar to Fig. 2 but illustrating the turret in the position it occupies at the end of the buttonhole;

Fig. 15 is a section on the line 15—15, Fig. 13;

Fig. 16 is a section on the line 16—16, Fig. 14;

Fig. 17 is a fragmentary view showing the operation of the pull-off for the upper thread.

In the drawings 1 indicates the frame of the sewing machine which carries the stitch-forming mechanism, the latter comprising the upper needle 2 mounted in the vertically-reciprocating needle bar 3 and operating from above the work, and under-thread mechanism, indicated generally at 4, and situated beneath the work.

The frame 1 is mounted on the bed 31 which carries the work clamps 46 by which the work is clamped in position. The stitch-forming mechanism and the work clamps have a relative movement during the sewing on the buttonhole as usual in buttonhole sewing machines and in this construction this relative movement is secured by reason of the

fact that the frame 1 is allowed to move back and forth on the bed 31.

As stated above, the sewing machine herein shown is of that type in which the stitch-forming mechanism is mounted to rotate at each end of the buttonhole and for this purpose the under thread mechanism 4 is mounted on the usual turret 5 which carries at its upper end the throat plate 6 having the sewing opening 7 through which the upper needle operates, said turret being mounted to rotate in suitable bearings 8. The needle bar 3 with the needle 2 is also mounted to rotate and the means herein shown for giving the turret and the needle bar their rotational movements at each end of the buttonhole is such as is commonly employed in buttonhole sewing machines.

This rotational movement is secured from 20 a vertically-arranged rock shaft 9 journaled in the frame and carrying at its upper end a segmental gear 10 meshing with a gearing 11 by which the needle bar is turned, said shaft carrying at its lower end another segmental gear 12 which meshes with a gear 13 on the turret 5. The turning movement of the rock shaft 9 is secured at proper times from the main cam 14 which is mounted in the usual cam casing 15 that is secured to the frame 1.

25 The rock shaft 9 has the arm 16 rigid therewith which is connected by a link 17 to the end of a lever 18 pivoted to the cam housing at 19, said lever being given a vibrating movement from full to dotted line position Fig. 4 through the medium of a cam groove (not shown) formed in the main cam 14. This means for rotating the stitch-forming mechanism is such as is commonly employed in buttonhole sewing machines.

30 The machine herein shown is also provided with buttonhole cutting mechanism for cutting the buttonhole slit. This cutting mechanism comprises two cutting elements 20 and 21, one of which is a cutting blade and 45 the other of which is a cutting block. The element 20 is shown as mounted on a lever 22 pivoted to the frame at 23 and having at its rear end a follower 24 adapted to be engaged by a cam projection 25 on the main cam 14, said cam projection being so disposed that at 50 the proper time in the sewing cycle the lever 22 will be actuated to bring the cutting element 20 into operative position. The other cutting element 21 is movably mounted, it normally being in its retracted position shown in Fig. 1 during the sewing on the buttonhole but being moved forward into its operative position shown in Fig. 13 at the time that 55 the lever 22 is actuated.

60 Either cutting element may be the cutting blade and the other the cutting block. In the construction shown the member 20 is in the form of a block and the member 21 has the cutting edge but so far as the invention is concerned the member 20 may have the cutting

edge and the member 21 might be in the form of a block.

The cutting member 21 is carried by a block 26 which is adjustably carried by a slide 27 that slides back and forth in ways 28 formed on the cam casing 15. The block 26 is retained in its adjusted position on the slide 27 through the medium of clamping screws 29.

As stated above the cutting element 21 and the block 26 on which it is mounted are normally in retracted position shown in Figs. 1 and 2 but they are moved forward into the operative position shown in Figs. 13 and 9 by the operative movement of the lever 22.

This is accomplished by the following mechanism. Slidably mounted in bearings 30 carried by the stationary bed 31 of the machine is a controlling rod 32, the latter having an arm 33 fast thereto, the end 34 of which extends into an opening formed in the side of the block 26. This rod 32 is provided with a notch 35 in which is received the lower end of a lever 36, the latter being pivoted at 37 to a bracket 38 on the frame 1. This lever is provided with a cam surface 39 adapted to be engaged by a roller 40 on the end of a lever 41 pivoted at 42 to the frame, said lever having at its rear end a lateral projection 43 adapted to be engaged by the rear end of the lever 22. The lever 41 is acted on by a spring 44 which tends to hold it in the position shown in Fig. 1 and the lever 36 is acted on by a return spring 45.

When the lever 22 is actuated to bring the cutting element 20 into operative position the upward movement of the rear end of the lever will rock the lever 41 thereby causing the roll 40 to engage the cam surface 39 and swing the lever 36 forwardly into the position shown in Fig. 13. Such movement of the lever will carry the rod 32 forwardly thereby moving the slide 27 forwardly and placing the cutting element 21 into its operative position shown in Fig. 13. Hence, as the cutting element 20 moves downwardly the co-operating element 21 will move forwardly into position beneath the element 20 and the two elements will serve to cut the buttonhole slit in the work which is then held in place by the work clamps 46.

One feature of my present invention relates to means associated with the buttonhole cutting mechanism for cutting the upper thread at the end of the sewing operation. As usual, in buttonhole sewing machines the stitch-forming mechanism is so constructed that when the machine comes to rest with the needle 2 raised as shown in Fig. 1 there will be a loop 47 of the upper thread retained by the loopers 140 of the under thread mechanism, the upper thread extending from the eye of the needle through the work and forming the loop 47, one leg 48 of which is connected to the last stitch.

I have provided herein means associated

with the cutting element 21 for cutting the leg 48 of the loop 47 as the buttonhole slit is cut. This is accomplished by a cutter 49 that is carried by the block 26 and is situated in front of the cutting element 21. This cutting blade 49 is so disposed that when the cutting element 21 moves forwardly into its operative position as shown in Figs. 9 and 13 said cutting blade 49 will pass underneath the throat 6. This blade 49 is formed with the hook portion 50 having its front edge 51 curved and its rear edge 52 formed as a cutting edge.

During the movement of the cutter 49 into the position shown in Figs. 9 and 13 the leg 48 of the loop 47 will engage the curved face 51 and will be deflected thereby behind the hook 50 as shown in Fig. 13 so that during the buttonhole cutting operation the leg 48 of the loop 47 is located in the rear of the hook 50. When the cutting of the buttonhole is completed and the follower 24 passes off from the cam 25 the springs 44 and 45 will return the slide 27 and cutting element 21 to their normal retracted position, this return movement being a rapid one. During the return movement the cutting edge 52 will sever the leg 48 of the loop 47 directly beneath the throat 6. The cutting of the upper thread, therefore, is accomplished by means associated with the buttonhole cutting mechanism.

I have also provided herein means for engaging the upper thread and pulling the cut loop 47 back through the work so as to leave a sufficient length of thread projecting from the eye of the needle 2 to permit of the proper formation of the first stitch on the next buttonhole. This pulling out of the loop is accomplished by a pull-off lever 53 (see Figs. 1, 5 and 17) which is pivoted to the frame 1 at 54. The end of the pull-off lever is formed with a thread-retaining notch 55. During the sewing on the buttonhole said lever is in the full line position Fig. 5, it being retained therein by means of a spring 156. As the buttonhole is cut the lever is swung into the dotted line position Fig. 5 during which movement the notched end wipes by the length 50 of upper thread *t*, said lever being so arranged that when it is in the dotted line position said thread is in line with the notch 55. After the buttonhole is cut the lever 53 is swung back into the full line position during which movement the thread *t* is engaged by the notch 55 and the movement of the pull-off pulls the cut loop out through the work.

For thus operating the pull-off device the lever 22 is provided with a finger 56 which is situated above the inclined pull-off arm 53 as shown in Fig. 5. When the lever 22 makes its operative movement this finger 56 will engage the lever 53 and will swing it back into the dotted line position and as soon as the buttonhole has been cut and the arm 22 is re-

turned to its raised position the spring 156 will return the pull-off arm 53 to its operative position thus pulling off the cut loop of upper thread.

For cutting the under thread, as well as stay cord, if one is used, I propose to employ a cutter 57 which is carried by a rock shaft 58 journaled in one of the clamp plates 59, said cutter having the cutting edge 60. This thread cutter is similar to thread cutters which have heretofore been used for cutting the under thread and it is in the form of a plate operating directly above the clamp plates and thus lying underneath the work.

When the sewing on the buttonhole has been completed the cutter 57 is swung from the full to the dotted line position Fig. 6 thus carrying the cutting edge 60 across the sewing opening of the throat 6 which at this time in the sewing circle is located in the position shown in Fig. 6. This cutting movement of the thread cutter 57 will sever the under thread close to the work and between the latter and the throat and will also cut the stay cord, if one is used.

In the present embodiment of my invention the operative movement of the thread cutter 57 is derived from the means for rotating the stitch-forming mechanism.

It will be understood by those skilled in the art that after the sewing on the buttonhole has been completed the stitch-forming mechanism is driven a half rotation to return it to proper position to begin the sewing on the next buttonhole and it is during this rotation of the stitch-forming mechanism that the cutter 57 is operated.

The rock shaft 58 has fast thereto an arm 61 which is adapted to be engaged by a projection 62 carried by a slide 63. This slide 63 is guided at one end by a guiding pin 64 which is mounted on the under side of the bed 31 and extends through a slot 65 in the slide, the other end of the slide being pivotally connected to a lever 66 which is pivoted to the bed at 67. This lever has at its rear end a latch member 68 adapted to be engaged by a projection 69 formed on the link 17. The lever 66 is acted on by a return spring 70 which normally holds it in the position shown in Fig. 4.

The sewing machine herein shown is of that type in which the frame 1 moves back and forth on the bed 31 during the stitching along the sides of the buttonhole, said frame and cam casing moving from the full to the dotted line position, Fig. 4, when sewing down the first side of the buttonhole and then returning to the full line position when sewing the second side of the buttonhole. When the sewing on the buttonhole has been completed the parts are in the full line position Fig. 4 with the projection 69 behind the latch 68. At this time the main cam 14 moves the lever 18 from the full to the dotted

line position Fig. 4 thereby to give the stitch-forming mechanism the required half rotation to bring it to initial position and during such movement of the lever 18 the projection 69 will engage the latch 68 and will swing the lever 66 into the dotted line position, which movement will cause the projection 62 of the slide 63 to turn the arm 61 thereby swinging the cutter 57 from the full 10 to the dotted line position Fig. 6.

Before the lever 18 completes its movement to the dotted line position the projection 69 will be carried out of engagement with the latch 68 thus allowing the lever 66 to be returned to its initial position by the spring 70. The cutter 57 is also returned to its initial position by a spring 71. The cutting of the under thread, and stay cord also if one is used, is thus accomplished by the 15 means which gives the turret its rotation at the end of the buttonhole.

I have also provided novel means for gripping the under thread u after it is cut and holding the cut end until after the first few 20 stitches have been completed on the next buttonhole, and I have further provided means co-operating with the thread-gripping device to pull off a length of under thread after the latter has been gripped thereby to provide sufficient slack thread to enable the first 25 stitches to be properly formed.

The under thread u extends from the source of supply through a suitable guiding tube 72 carried by the turret, thence through the 30 under thread tension 73 comprising the usual tension disks 74, 75 between which the thread passes and which are held in frictional contact with the thread by the spring 76, thence through a guide eye 77 at the end of a 35 silent pull-off arm 78, thence through another guiding tube 79 to one of the loopers of the under thread mechanism and from the looper through an opening 80 in the throat 6 which leads to the sewing opening thereof, this being the usual way of threading up 40 under thread mechanism of this type.

The means for gripping the under thread u at the end of the sewing operation comprises a gripping finger 81 which co-operates with 45 a shoulder 82 formed on the throat 6 adjacent the opening 80, said shoulder being so disposed that the thread passes over the shoulder as it is led through the throat 6. This thread-gripping finger 81 is normally separated from the shoulder 82 as shown in Fig. 10 but at the end of the sewing operation it is moved into engagement with the shoulder as shown in Fig. 9 thereby gripping the under 50 thread u , and it remains in this operative position until the sewing has started on the next succeeding buttonhole, at which time it is returned to its inoperative position shown in Fig. 10 thereby releasing the under thread.

This finger 81 is carried by a bar 83 which 55 is pivotally mounted on centers 84 carried by

the turret. This bar has a leaf spring 85 secured thereto which bears against the turret and which normally tends to swing the thread-clamping arm into its operative position.

As stated above said arm is held in its inoperative position during the sewing of the buttonhole. The means for accomplishing this in the construction herein shown comprises a slide 86 carried in a suitable guide 60 mounted on the turret and having a projection 88 provided with a cam face 89. When the slide 86 is in the position shown in dotted lines Fig. 14 the projection 88 occupies an opening 90 in the thread-gripping finger 81 and at this time the spring 85 will hold the gripper in its operative position. If the slide 86 is moved into the position shown in Fig. 11 then the cam face 89 of the projection 88 engages the inclined face 91 at the end of the opening 90 with the result that the finger 81 is cammed or forced backwardly into its inoperative position. The movement of the slide 86 is sufficient so that the projection 88 can be carried behind said finger and thus when the parts are in the position shown in Fig. 11 the gripping finger is held in its inoperative position by the projection 88. This is the position which the parts assume during the sewing on the buttonhole.

I have provided herein means operative when the sewing on the buttonhole is completed to move the slide to the left Fig. 11, or to the right Fig. 14, thereby releasing the gripping finger and allowing it to move into gripping engagement with the under thread u .

It will be remembered that the turret 5, on which the slide 86 is mounted, has a half revolution at each end of the buttonhole. During the stitching on the first side of the buttonhole the turret is in the position shown in Fig. 2 and the frame 1 with the turret is moving backwardly or toward the top of Fig. 2. When the first side of the buttonhole has been sewed the turret is given a half rotation to sew around the eye of the buttonhole and then during the sewing of the second side of the buttonhole the frame 1 on which the turret is mounted is moved forwardly thus bringing the turret into the position shown in Fig. 14. As the buttonhole is completed the end 92 of the slide 86 is situated opposite the end 93 of a lever 94 which is pivoted at 95 to the bed plate and means are provided which become operative at the completion of the buttonhole to swing the lever 94 thereby causing it to shift the slide 86 into a position to release the thread-gripping finger 81 thereby allowing said finger to clamp the under thread u against the shoulder 82. This operative movement is given to the lever 94 through the medium of the rod 32 which, it will be remembered, is

the rod that moves the cutting element 21 into its operative position.

The lever 94 is shown as having a cam face 96 and the rod 32 is provided with a collar 97 situated to engage the cam face when the rod 32 is given its operative movement. Hence when the buttonhole cutter is actuated to cut the buttonhole the lever 94 will be turned into the dotted line position Fig. 14 by the collar 97 and such movement of the lever 94 will shift the slide 86 and thus render the under-thread gripping finger 81 operative.

Simultaneously with the gripping of the under thread by the finger 81 a length of under thread will be drawn through the tension 73. This is provided for by the action of the pull-off arm 78 together with the releasing of the frictional pressure of the tension 73 on the under thread.

The arm 78 is made of light spring and during the sewing operation the tension on the under thread μ will be sufficient so that the arm will be in the dotted line position Fig. 8. If the tension 73 is released, however, the resiliency of the arm 78 will cause it to move into the full line position Fig. 8 thus drawing a length of thread through the tension, it being remembered that the under thread is held by the gripping finger 81.

Means are provided for releasing the tension 73 simultaneously with the gripping of the under thread by the finger 81. To accomplish this the bar 83 is provided with a depending finger 98 which acts against one end of a lever 99 pivoted to the turret at 100, the other end of said lever acting against one end of a thrust pin 101 which finds a bearing in the turret, said thrust pin in turn acting against a follower 102 against which the tension spring 76 bears.

Under normal operation the disk 102 rests against the tension disk 74 so that the pressure of the spring 76 is applied to the tension disk, this being the position of the parts when the clamping finger 81 is in its inoperative position shown in Fig. 10. When said clamping finger is moved into its operative position, however, the depending arm 98 rocks the lever 99 thus moving the thrust pin 101 into the position shown in Fig. 12 and thereby taking the spring tension off from the tension disks. As soon as this tension is relieved the resiliency of the pull-off arm 78 causes it to move into the full line position Fig. 8 thus drawing off a length of under thread as above described.

It will thus be seen that the tension 73 and the thread-gripping arm 81 operate in opposition, the tension being operative when the thread-gripping arm is in inoperative position, as shown in Figs. 10 and 11, and the tension being inoperative when the thread-gripping arm is in operative position, as shown in Figs. 9 and 12.

I have described above how the thread-

gripping finger 81 is brought into its operative position shown in Figs. 2 and 9 at the end of the sewing operation. Said finger remains in this operative position until after the stitching has begun on the next buttonhole at which time the finger is again thrown into its inoperative position by shifting the slide 86 into the position shown in Fig. 11.

For accomplishing this I have provided the following mechanism. Pivotally mounted on the turret bearing at 103 is a lever 104 which is acted upon by a suitable spring 105, said spring normally holding the lever against the stop 106. The slide 86 is formed at its end 92 with the ear 107. It will be remembered that the turret is in the position shown in Fig. 2 during the sewing on the first side of the buttonhole and that it makes a half rotation into the position shown in Fig. 14 in sewing around the eye of the buttonhole so that at the completion of the buttonhole it is in the position shown in said Fig. 14. Before the sewing begins on the next buttonhole the turret is given a reverse half rotation to bring it back into the position shown in Fig. 2 and as the turret completes its reverse half rotation the ear 107 is carried around the end 108 of the lever 104 as shown in Fig. 2. During the formation of the first stitches on the buttonhole the lever 104 is swung from the position shown in Fig. 2 to that shown in Fig. 11, such swinging movement causing the end 108 to engage the lug 107 and thus give the slide 86 its operative movement. This movement of the lever 104 is secured from a pin 109 mounted in a bracket 110 secured to the bed 31 of the machine.

It will be remembered that during the sewing on the buttonhole the frame 1 with the turret is moving backwardly or toward the top of the sheet in Figs. 2 and 11. The pin 109, however, is carried by the stationary bracket 110 and hence as the frame 1 begins its feeding movement the cam face 111 on the lever 104 engages the pin 109 and thereby causes the lever to have its operative movement as shown in Fig. 11. The feeding movement of the frame 1 is sufficient so that the end of the lever 104 is carried beyond the pin 109 and as soon as this occurs the spring 105 will restore the lever to the position shown in Fig. 2. The slide 86, however, will remain in its operative position until it has been restored to the dotted line position shown in Fig. 14 by the lever 94, as above described.

The pin 109 is yieldingly mounted as shown in Fig. 3, it being supported in a sleeve 112 and backed by a spring 113. The under face of the end of the lever 104 is bevelled as shown at 114. When the first side of the buttonhole has been completed the end of the lever 104 will be in the dotted line position Fig. 11 and during the return movement of the frame 1 as the second side of the buttonhole is being sewed the bevelled face 114 of the lever 104

will engage the pin 109 and depress the latter, thus allowing the end of the lever to pass over the pin without being operated. When the frame 1 has had its complete return movement the parts are in the relative position shown in Fig. 2, the end of the lever 104 having passed off from the pin 109 so that the latter can rise under the influence of the spring 113.

With the parts in this position the pin is adjacent the cam face 111 so that upon the next forward movement of the frame 1 said pin will actuate the lever 104. This pin and bevelled face 114 thus form a sort of switch cam which is operative during the movement 15 of the frame in one direction but is inoperative during the movement in the opposite direction.

It will be noted that the under thread cutter 57 operates above the throat while the upper thread cutter 49 operates beneath the throat. The devices for operating these cutters are so timed that the upper thread cutter 49 will function first to cut the loop 47 of upper thread, which loop is immediately pulled out from the cloth by the pull-off 53, and subsequently the under thread cutter 57 is actuated to cut the under thread and stay cord, if one is used, above the throat plate.

While I have illustrated herein a selected embodiment of the invention I do not wish to be limited to the constructional features shown.

I claim:

1. In a buttonhole sewing machine, the combination with stitch-forming mechanism, of buttonhole-cutting mechanism comprising two buttonhole-cutting elements movable relative to each other, and a thread cutter secured to one of said elements.
2. In a buttonhole sewing machine, the combination with stitch-forming mechanism, of buttonhole-cutting mechanism comprising two co-operating cutting members, and a thread cutter carried by one member.
3. In a buttonhole sewing machine, the combination with stitch-forming mechanism, of buttonhole-cutting mechanism comprising a cutter and a cutting block movable toward and from each other and a thread cutter carried by one of said elements.
4. In a buttonhole sewing machine, the combination with stitch-forming mechanism, of buttonhole-cutting mechanism comprising a buttonhole cutter movable into and out of cutting position, a block co-operating with the cutter, and a thread cutter carried by the buttonhole cutter.
5. In a buttonhole sewing machine, the combination with stitch-forming mechanism, of buttonhole-cutting mechanism comprising a buttonhole cutter movable horizontally into and out of operative position, a cutting block co-operating with the cutter and a thread cutter carried by the buttonhole cutter.

6. In a buttonhole sewing machine, the combination with stitch-forming mechanism, of buttonhole-cutting mechanism comprising two co-operating cutting members, a pivoted lever carrying one of said members, a horizontally-moving slide carrying the other member, means actuated by the lever to give movement to the slide and thereby bring the member carried thereby into operative position, and a thread-trimming knife carried by the slide. 70

7. In a buttonhole sewing machine, the combination with stitch-forming mechanism for concatenating an upper and an under thread, of buttonhole-cutting mechanism comprising two buttonhole-cutting elements movable relative to each other and means secured to one of said elements to cut the upper thread. 80

8. In a buttonhole sewing machine, the combination with stitch-forming mechanism for concatenating an upper and an under thread, of buttonhole-cutting mechanism comprising two co-operating cutting members, and a thread cutter carried by one of said members for cutting the upper thread. 85

9. In a buttonhole sewing machine, the combination with stitch-forming mechanism for concatenating an upper and an under thread, of buttonhole-cutting mechanism comprising two co-operating cutting members, a lever carrying one of said members, a horizontally-moving slide on which the other member is mounted, means to move the slide to bring the cutting member carried thereby 95 into operative position, and a thread cutter for trimming the upper thread carried by the slide. 100

10. In a buttonhole sewing machine, the combination with stitch-forming mechanism comprising upper thread handling mechanism and under thread mechanism arranged so that when the machine comes to rest a loop of upper thread is retained by the under thread mechanism, of buttonhole-cutting mechanism comprising two co-operating cutting members, and means carried by one member for cutting one leg of said loop of upper thread. 105

11. In a buttonhole sewing machine, the combination with stitch-forming mechanism comprising upper thread handling mechanism and under thread mechanism arranged so that when the machine comes to rest a loop of upper thread is retained by the under thread mechanism, of buttonhole-cutting mechanism comprising two co-operating cutting members, a horizontally-moving slide on which one of the members is mounted, means to give said slide its operative movement at the end of the sewing operation, and a knife carried by said slide for cutting one leg of said loop of upper thread. 110

12. In a buttonhole sewing machine, the

combination with stitch-forming mechanism comprising upper thread handling mechanism and under thread mechanism arranged so that when the machine comes to rest a loop of upper thread is retained by the under thread mechanism, of buttonhole-cutting mechanism comprising two co-operating cutting members, means carried by one member for cutting one leg of said loop of upper thread, and means to pull the cut loop out from the work.

13. In a buttonhole sewing machine, the combination with stitch-forming mechanism comprising upper thread handling mechanism and under thread mechanism arranged so that when the machine comes to rest a loop of upper thread is retained by the under thread mechanism, of buttonhole-cutting mechanism comprising two co-operating cutting members, a horizontally-moving slide on which one of the members is mounted, means to give said slide its operative movement at the end of the sewing operation, a knife carried by said slide for cutting one leg of said loop of upper thread, and means to pull the cut loop out from the work.

14. In a buttonhole sewing machine, the combination with stitch-forming mechanism for concatenating an upper and under thread and constructed so that when the machine comes to rest a loop of upper thread is retained by the under thread mechanism, of button-hole-cutting mechanism comprising two cooperating cutting elements, a lever on which one element is mounted, a cam for operating said lever, a slide on which the other cutting element is mounted, means actuated by said lever to move the slide to carry the cutting element thereon into operative position, a thread cutter carried by said slide and adapted to cut one leg of the loop of upper thread, and means actuated by said lever to pull said loop back through the work.

15. In a buttonhole sewing machine, the combination with stitch-forming mechanism, of means to rotate said mechanism at the end of the buttonhole, and means actuated by the stitch-forming mechanism rotating means to cut the thread.

16. In a buttonhole sewing machine, the combination with stitch-forming mechanism adapted to concatenate an upper and an under thread, of means to rotate said mechanism at the end of the buttonhole, and means actuated by the devices by which the stitch-forming mechanism is rotated to cut the under thread.

17. In a buttonhole sewing machine, the combination with stitch-forming mechanism comprising upper and under thread handling mechanism, a turret carrying the under thread mechanism, means to rotate the turret at the end of the buttonhole, and means actuated by the turret-rotating means to cut the under thread.

18. In a buttonhole sewing machine, the combination with stitch-forming mechanism comprising upper thread mechanism and under thread mechanism, a turret carrying the under thread mechanism, said turret having a throat, means to rotate the turret at the end of the buttonhole, and means actuated by the turret-rotating means to cut the under thread above the throat and beneath the work.

19. In a buttonhole sewing machine, the combination with stitch-forming mechanism comprising upper thread mechanism and under thread mechanism, a turret carrying the under thread mechanism, said turret having a throat, means to rotate the turret at the end of the buttonhole, means actuated by the turret-rotating means to cut the under thread above the throat and beneath the work, and means on the turret to grip the under thread.

20. In a buttonhole sewing machine, the combination with stitch-forming mechanism for concatenating an upper and an under thread, of means to rotate said mechanism at the end of the buttonhole, means actuated by the devices by which said mechanism is rotated to cut the under thread and means to hold the cut end.

21. In a buttonhole sewing machine, the combination with stitch-forming mechanism for concatenating an upper and an under thread, of means to rotate said mechanism at the end of the buttonhole, a cutter for the under thread, a gripping finger to grip the under thread, means actuated by the devices by which said mechanism is rotated to give the cutter its cutting movement and means to control the operation of the gripping finger.

22. In a buttonhole sewing machine, the combination with stitch-forming mechanism for concatenating an upper and an under thread, means to rotate said mechanism at the end of the buttonhole, a cutter for cutting the under thread, a spring-pressed gripping finger to grip the under thread, means normally holding the gripping finger in inoperative position, means actuated by the devices by which said mechanism is rotated to operate the cutter and means to release the gripping finger.

23. In a buttonhole sewing machine, the combination with stitch-forming mechanism for concatenating an upper and an under thread, of means to rotate said mechanism at the end of the buttonhole, a tension for the under thread, means actuated by the devices by which said mechanism is rotated to cut the under thread, and means to grip the cut end and to relieve the tension.

24. In a buttonhole sewing machine, the combination with stitch-forming mechanism for concatenating an upper and an under thread, means to rotate said mechanism at the end of the buttonhole, of a tension for the

under thread, means actuated by said last-named means to cut the under thread, means to grip the cut end and to relieve the tension, and means to draw off a length of under 5 thread when the tension is released.

25. In a buttonhole sewing machine, the combination with stitch-forming mechanism for concatenating an upper and an under thread, of means to rotate said mechanism

10 at the end of the buttonhole, means actuated by the last-named means to cut the under thread, means to grip the cut end, and means to release said cut end after the stitching has begun on the next buttonhole.

15 26. In a buttonhole sewing machine, the combination with stitch-forming mechanism for concatenating an upper and an under thread, of means for rotating said mechanism at the end of the buttonhole, a spring-pressed

20 gripping finger to grip the thread, a cutter to cut the thread between the gripping finger and the work, means normally holding the gripping finger inoperative, means operated by the devices by which said mechanism is

25 rotated to operate the cutter, means to release the gripping finger, whereby the latter becomes operative to grip the thread, and means to render the gripping finger inoperative after the first stitches have been formed

30 on the next succeeding buttonhole.

27. In a buttonhole sewing machine, the combination with stitch-forming mechanism and work-holding means having a relative movement, means to rotate said mechanism

35 at the end of the buttonhole, a thread-gripping finger to grip the under thread, a cutter to cut said thread between the gripper and the work, means actuated by the devices for rotating said stitch-forming mechanism to

40 operate the cutter, means to render the gripping finger operative, and means operated by said relative movement to release the gripping finger after the stitching has begun on the next buttonhole.

45 28. In a button-hole-sewing machine, the combination with stitch-forming mechanism, of buttonhole-cutting mechanism, means to cut the under thread at the end of the sewing operation, and means controlled by the but-

50 tonhole-cutting mechanism to grip the under thread.

29. In a buttonhole-sewing machine, the combination with stitch-forming mechanism, of buttonhole-cutting mechanism, means to

55 cut the under thread at the end of the sewing operation, a spring-actuated thread-gripping finger to grip the under thread between the point where it is cut and the source of supply, means normally holding the finger inoperative, and means actuated by the button-

60 hole-cutting mechanism to release said finger after the thread has been cut.

30. In a buttonhole-sewing machine, the combination with stitch-forming mechanism, of buttonhole-cutting mechanism, means to

rotate said stitch-forming mechanism at the end of the buttonhole, means actuated by the devices by which said mechanism is rotated to cut the thread, and means controlled by the buttonhole-cutting mechanism to grip 70 the cut end.

In testimony whereof, I have signed my name to this specification.

JOHN KIEWICZ.
